UNITED STATES PATENT OFFICE.

HENRY AUCHU, OF EMPORIUM, PENNSYLVANIA.

MACHINE FOR PACKING DYNAMITES AND OTHER HIGH EXPLOSIVES INTO SHELLS.

1,071,683.

Specification of Letters Patent.

Patented Sept. 2, 1913.

Application filed July 26, 1910. Serial No. 573,993.

To all whom it may concern:

Be it known that I, HENRY AUCHU, a citizen of the United States, residing at Emporium, county of Cameron, and State 5 of Pennsylvania, have invented certain new and useful Improvements in Machines for Packing Dynamites and other High Explosives into Shells, of which the following is a specification.

10 The present invention relates to machines for packing dynamites and other high explosives into shells which may be conveniently used for blasting and other purposes.

15 Dynamites and other high explosives are most frequently packed into paper shells by hand on account of the extreme danger of the operation.

20 The present invention has for its object the provision of a novel machine, susceptible of many modifications within the scope of the appended claims, which will be adapted to automatically, rapidly and safely carry out the operation of packing the shells and whereby a number of shells may be 25 simultaneously packed, but the packing operation of each will be independent of the others, so that each shell will be satisfactorily packed or filled.

30 In carrying out the invention, I provide means for gently but regularly packing the shells with the explosive; means for feeding the explosive to the packing devices; means for regulating the pressure of the packing action; means whereby the 35 packing operation will cease automatically when a shell is filled and which will permit any of the packing devices to stop when their shells are filled without interfering with the continuation of the packing of the 40 remaining shells which have not been filled, together with various other improved and novel instrumentalities, as will more fully appear hereinafter.

45 In the accompanying drawings: Figure 1 is a side elevation, partly in section, showing one form of the invention with the auger raised; Fig. 2, a front elevation thereof; Fig. 3, a detail plan of one of the pulleys; Fig. 4, a front elevation showing part 50 of a modified machine; Figs. 5, 6 and 7, details of modified screw packers.

55 Referring first to Figs. 1, 2 and 3, illustrating the first form of the invention, the framework of the machine is shown at 1, and it carries an inclined hopper 2 having

an open front and provided with a front wall 3.

The numeral 4 designates a feeder which has spurs or paddles 5 operating in the lower front part of the hopper and adapted 60 to gently urge the dynamite or other high explosive toward the feeding devices and into the shells. The inclination of the hopper bottom may be changed as desired, according to the consistency or nature of the 65 explosive to be operated upon, so that the gravitational action thereof will carry such explosive downwardly and forwardly to the feeder. The front part of the hopper bottom adjacent to the wall 3 is provided with 70 any desired number of funnel shaped openings in which the removable funnels 6 are placed, the paper shells to receive the dynamite or explosive being shown at 7 and held in a split or divided holder 8, which is suitably supported by the frame 1. A number 75 of these holders 8 may be employed in which the operator will place the shells 7 so that as soon as one set is filled, the holder and the filled shells may be quickly removed and another holder with empty shells inserted in place thereof, thus insuring great 80 rapidity of operation without any loss of the explosive. On separating the halves of the holder, the shells may be removed. 85

Journaled in suitable bearings 9 are the shafts 10 of the packing augers 11, which are detachably connected by couplings 12 to said shafts, thus permitting the augers 11 to be made of bronze, aluminum or other 90 suitable material and the shafts 10 of brass, cheapening the construction. The packing augers 11 are of suitable length and size to pass through the funnels 6 and into the shells 7, and in order that the lower ends of the augers may not quite reach to the bottoms of the shells, adjustable collars 13 are provided on the respective shafts 10 which, by their 95 abutment with the upper bearings 9, limit the extreme downward play of the augers. 100 The shafts 10 each carry a key 14. Supported in bracket bearings 15 secured to frame 1, are wheels or pulleys 16, through which the shafts 10 loosely pass, the hubs of the pulleys or wheels 16 having key-seats 105 17 adapted to receive the keys 14. As many disk weights 18 as desired may be attached to the upper ends of the shafts 10. These weights can be supported by a separate weight and collar 19 held by a set screw, 110

or they may be supported by the collar 18. According to the number of weights or avoidropois thereof, the packing pressure exerted by the packing augers 11 on the 5 dynamite or explosive will be varied, and means are thus provided to accommodate the machine to any particular explosive which is being packed. All of the wheels of pulleys 16 are connected by belts 20 to 10 wheels on a suitable countershaft 21. Figs. 5 and 6 and 7 show other forms of the screw packers which may be used.

The dynamite or other explosive having been placed in the hopper and the machine 15 started, the explosive will gravitate toward the funnels 6 and will be gently urged against the augers 11 by the paddles 5 of the feeder, and because the augers are within the shells, the keys 14 will be received in 20 the seats 17 and the augers will be in rotation in a direction which will be the opposite of boring, and hence the explosive will be fed or packed into the shells. As the packing continues, the augers automatically rise 25 on account of the filling of the shells until, when the shells are finally packed or completely filled, the augers will be in such position that the keys 14 will have passed out of the seats 17 (Fig. 3) and hence the rotation of the pulleys 16 will not cause rotation of the shafts 10, and the augers will remain at rest. Each packing device being 30 independent of all others, certain of the shells may be packed before the packing of others is completed, but there is no interference of operations and when all of the shells are packed, the holder 8 is removed 35 with the filled shells and another holder carrying empty shells is substituted therefor.

40 Referring to Fig. 4, the construction is identical with that heretofore described with the exception that the driving means consists of a shaft 22 having a worm 23 meshing with worm wheels 24 loosely car-

ried by the respective shafts 10, the worm 45 wheels 24 having key-seats like the key-seats 17.

Having thus described my invention, what I claim as new and desire to secure by Letters Patent, is:—

1. In a shell packing machine, the combination with a shell holder, of a rotatable and slidable shell packer having an inclined packing flange or surface and a stem adapted to fill a shell held by said holder and to retreat as the shell is filled, a wheel through which the shell packer slides and by which it is rotated, a loose spline connection between said wheel and packer, the parts of which are engaged while the shell 55 is being packed and which is adapted to entirely disengage when the shell has been packed.

2. In a shell packing machine, the combination with a shell holder, of a rotatable 65 and slidable shell packer having an inclined packing flange or surface and a stem adapted to fill a shell held by said holder and to retreat as the shell is filled, a wheel through which the shell packer slides and 70 by which it is rotated, a loose spline connection between said wheel and packer, the parts of which are engaged while the shell is being packed and which is adapted to entirely disengage when the shell has been 75 packed, and a plurality of separately removable weights carried by and movable with said stem for applying any desired pressure to the shell packer to thereby regulate the density of the material loaded into 80 the shell.

In testimony whereof, I hereunto affix my signature in presence of two witnesses.

HENRY AUCHU.
